UNITED STATES PATENT OFFICE.

ORTON B. BROWN AND HOWARD PARKER, OF BERLIN, NEW HAMPSHIRE, ASSIGNEES
TO BROWN COMPANY, OF PORTLAND, MAINE, A CORPORATION OF MAINE.

APPARATUS FOR TREATING ARTICLES MADE FROM PULP.

Application filed September 26, 1921. Serial No. 503,336.

To all whom it may concern:

Be it known that we, ORTON B. BROWN and HOWARD PARKER, citizens of the United States, and residents of Berlin, in the county 5 of Coos, State of New Hampshire, have invented certain new and useful Improvements in an Apparatus for Treating Articles Made from Pulp, of which the following is a specification.

19 This application is a continuation in part of our application, Serial No. 200,615, filed November 6, 1917, for apparatus for treating articles made from pulp.

This invention relates particularly to apparatus for impregnating walls of pulp pipes, tubes or similar articles, with a material having certain desired characteristics such, for instance, as water-proofing and electrical insulating qualities.

20 In the accompanying drawings:—

Fig. 1 is a diagrammatic layout, in plan, of the installation of the apparatus,

Fig. 2 is an end view, partly in transverse section, of what is shown in Fig. 1, and

Fig. 3 is a detail view showing more or less conventionally the means for governing the temperature of the impregnating material.

This invention has been developed in connection with the treating of articles made of pulp, for instance, pulp pipes or tubes or similar articles. Such a pipe may be formed by winding a sheet of pulp on a mandrel until a wall of sufficient thickness has been

35 formed, then removing the pipe from the mandrel and thoroughly drying it. The pipe must then be treated in such manner as the use to which it is to be put may determine. If used as a conduit for electrical

40 wiring, its walls must be thoroughly impregnated with a di-electric and it must also be waterproof. If it should be used for water pipe it must be thoroughly waterproofed. This invention has to do solely with the

45 treating of the tubes so that they shall be best adapted for the duty for which they are desired, and for convenience of description it will be considered that the pipes are to be impregnated with a special grade of pitch which is di-electric and waterproof.

50 Referring now to the drawings, it will be seen that the complete apparatus comprises a plurality or battery of treating units arranged along each side of a common storage tank *a* into which the melted pitch is

pumped in any suitable manner. Each of the units comprises a charging tank *b* adapted to communicate with the storage tank *a* and a treating tank *c* communicating, as hereinafter described, with the charging tank. The treating tanks are of such size that a large number of pipes can be treated at the same time, these pipes being supported in suitable cages *d*, the top and bottom walls of which are perforated as shown. These 60 cages, with the tubes therein, are adapted to be lowered into and removed from the tanks by a crane or the like. It is of course understood that the covers of the treating tanks are removable, and preferably these 65 covers are somewhat dome shaped so that gases may collect therein.

Positioned in each charging tank is a pump 11 continuously driven by a motor 12 or otherwise. Each pump 11 has an intake 13 opening into the charging tank *b* in which it is located, and the discharge end of the pump is connected with a pipe 14 which discharges into the treating tank near its upper end and is so arranged that the 70 material passing out of the pipe is projected substantially tangentially into the tank so as to have an initial circumferential or whirling action. 15 is a pipe leading from a multi-way cock 16 in the pipe 14 to the 75 storage tank *a*. 17 designates a pipe leading from the storage tank to a multi-way cock 18 in the intake of the pump. The fluid passes from the bottom of the treating tank to its charging tank through a large 80 pipe 19. It will be seen that with this arrangement, to charge the treating tank, the valves 16 and 18 are turned so that the pump will draw the treating fluid from the storage tank *a* through the pipe 17 and 85 force it into the treating tank through the pipe 14. After the treating tank has been charged, the valve 18 is turned to shut off the pipe 17 and open the inlet side of the pump directly to the charging tank whereupon the pump provides means for continuously circulating the impregnated material in the treating tank, taking it out of the bottom and returning it to the top. When the 90 treating has been carried to a sufficient extent and it is desired to remove the articles, the valves 16 and 18 may be turned to such positions that the treating material can be pumped out of the charging tank back into the storage tank. By so doing the treating 95

100

105

110

tank can be quickly and completely emptied before the cover is taken off and thus any loss of the impregnating material, due to vaporization, is eliminated. It has been found 5 that the best results are obtained by removing the impregnating material from the bottom of the treating tank and introducing it with a whirling action at the top.

It is essential that the treatment of the 10 pulp tubes be carried out substantially at a uniform pressure and that a proper supply of the treating material to the treating tank be maintained so that the tubes will always be covered. To these ends, the 15 bottom of each of the treating tanks is connected to what may be termed a pressure line 22 into which the treating fluid is pumped from the storage tank *a* by a positively acting pressure pump 23; the pump 20 23 being connected by a pipe 24 to the pressure line. The pressure line, at a point adjacent to that at which the impregnating material is supplied thereto, is provided with a discharge pipe 25 leading back to 25 the storage tank *a*, and in this discharge pipe 25 is a pressure regulator of any suitable type. This pressure regulator may be in the form of a relief valve 26, or similar apparatus, which can be either manually 30 set to maintain the proper pressure in the pressure line, or which may be automatically controlled through suitable devices. Each of the treating tanks is connected to the pressure line by a branch pipe 27 provided 35 with a one-way cock 28 so that any one of the treating tanks may be cut off from the pressure line when the treating tanks are being charged or emptied.

With this arrangement it will be seen that 40 there is a continuous flow of impregnating material through the pressure line and the pressure within this line or pipe is maintained uniform by the regulating device 26. In the event of excess pressure within the 45 pressure line, the regulator 26 will open allowing more of the fluid to flow back into the storage tank, and, if the pressure falls in the pressure line below a predetermined degree, the pressure regulator 26 will prevent any impregnating material going back 50 into the storage tank until the pressure is again built up. It will be found that the pulp tubes being treated will absorb considerable amounts of the impregnating material but this loss is automatically taken care of by the supply through the pressure line. Also it is found that gases are given off in the treatment of the pulp tubes but these gases which accumulate in the upper parts of the 55 tanks do not disturb the pressure within the treating tanks for they merely force the impregnating material back into the pressure line.

For the purpose of maintaining the impregnating material in a fluid state, the

storage tank and each of the treating and charging tanks are heated by steam coils located within them. In the present instance, the heating apparatus within the storage tank comprises an upper and lower 70 header 30, 31, respectively, connected by tubes 32. The upper header is connected by a pipe 33 to the steam supply pipe 34. The heating coils 36, 36' within the treating tanks and charging tanks, respectively, are connected by branch pipes to a common live steam line 35 which in turn is connected to the supply pipe 34. The exhaust steam pipe of the storage tank leads through a condenser drum 38 to a hot water well 39. The coils 36 and 36' of each unit are connected by a pipe 40 to exhaust steam pipes 41. In each of the pipes 40 is a condenser chamber or drum 42.

It is of extreme importance that the temperature in the treating tanks be maintained approximately uniform in order that the impregnating material shall be in the proper state of fluidity to most rapidly enter the wall of a pipe, but at the same time care must be taken that the heat is not sufficiently great to burn the fibers from which the pipe is made up, or cause the wall to split and laminate. For this reason each of the treating tanks is provided with separate means for automatically controlling the temperature of the impregnating material therein, and while this automatic means may be of any suitable kind or type, we have shown it, in the present instance, as being effected by governing the supply of steam to the coils 36, 36', and by controlling the release of the water of condensation from these coils, as follows: Interposed in each of the steam inlet pipes 37 is a valve 43 controlled by variations in the temperature of the impregnating material in the charging tank with which the particular valve 43 is associated. Interposed in each of the exhaust pipes 40 is a valve controlled by variations in the temperature of the water of condensation within the condenser drum or chamber 42 with which the particular valve 44 is associated. In the present instance, the control of the valves 43 and 44 is effected through the temperature regulator shown more particularly in Fig. 3. Positioned within each charging tank is a mercury or ether bulb 50 connected by a conduit 51 to a diaphragm 52 which acts through an adjusting cam 52' upon a valve 53 controlling the passage of air under pressure from the pipe 54 to the pipe 55 which leads to a diaphragm within a casing 46 connected to the valve 43. When the temperature within the treating tank rises beyond a predetermined degree, the mercury within the bulb 50 expands, raises the diaphragm 52, which in turn lifts valve 53 from its seat, allowing the air under pressure to flow through 120 125 130

- the pipe 55 and depress the diaphragm of the valve 43, thereby closing this valve so as to cut off the supply of steam to the heating coils 36, 36'. When the temperature falls below the above-mentioned predetermined degree, the valve 53 will be allowed to close and the spring of the valve 43 will cause the latter to open and again allow steam to flow to the heating coils. When the temperature 10 of the water of condensation in the condenser drum 42 falls below a predetermined degree the thermostatic device 58 with which this chamber is provided and which is similar to that indicated at 50, will operate the diaphragm 59 and thereby lower the valve 60 and shut off the flow of air under pressure to the pipe 61 thereby relieving the air pressure on diaphragm connected to the valve 44. The spring of this valve will now 20 cause this valve to open so as to allow the water of condensation to flow out of the condensing drum 42. It will be obvious that as the steam passes through the condensing chamber 42 the temperature thereof will be raised above a predetermined degree and the result is that the valve 60 will be raised into open position and the air pressure will act on the diaphragm of the valve 44 against the spring thereof to bring the valve 44 to its normal position corresponding to the predetermined temperature at which the device is set. If desired, the temperature of the impregnating material within the storage tank may be controlled by connecting up 30 with the valve 65 and the condenser 38 an arrangement such as is shown in Fig. 3 and which has just been described.
- In accordance with the provisions of the patent statutes we have described the principle of operation of our invention, together with the apparatus which we now consider to represent the best embodiment thereof; but we desire to have it understood that the apparatus shown is only illustrative, and 40 that the invention can be carried out by other means.
- We claim as our invention:—
1. In an apparatus of the character described, a treating tank, an outlet at the bottom thereof, an inlet at the top thereof tangentially arranged to give the incoming material an initial circumferential motion, and means for transferring the impregnating material from the bottom to the top of said tank.
  2. In an apparatus of the character described, a treating tank, a charging tank, an inlet at the top of said treating tank tangentially arranged to give the incoming material an initial circumferential motion, and means in the charging tank for transferring the impregnating material from the bottom of said treating tank to said inlet of said treating tank.
  3. In an apparatus of the character de-
- scribed, a treating tank, a charging tank, an inlet at the top of said treating tank tangentially arranged to give the incoming material an initial circumferential motion, and means in the charging tank for transferring the impregnating material from the bottom of said treating tank to said inlet of said treating tank, and means for heating said treating tank.
4. In an apparatus of the character described, a treating tank, a charging tank, a pump in the charging tank, connections between the inlet side of said pump and the bottom of said treating tank and between the discharge side of said pump and the top of said treating tank, means for driving said pump, and means for heating both of said tanks.
5. In an apparatus of the character described, a treating tank, a charging tank, a pump in the charging tank, connections between the inlet side of said pump and the bottom of said treating tank and between the discharge side of said pump and the top of said treating tank, and a multi-way valve located within the charging tank at the inlet and discharge sides of said pump.
6. In an apparatus of the character described, a treating tank, a charging tank, a storage tank, a pump in the charging tank, connections between the inlet side of said pump and the bottom of said treating tank and between the discharge side of said pump and the top of said treating tank, and connections between the storage tank and the inlet side of said pump and between the discharge side of said pump and said storage tank, and valves located within the charging tank at the inlet and discharge sides of said pump.
7. In an apparatus of the character described, a treating tank, means for constantly agitating the impregnating material in said tank, means for supplying heat to said tank, and means controlled by variations in the temperature of said impregnating material for governing the heat supply to said heating means.
8. In an apparatus of the character described, a treating tank, steam heating means for said tank having an inlet and an outlet, a condensation chamber connected to said outlet, and automatically operated thermostatically controlled valves associated with the inlet of said heating means and said condensation chamber.
9. In an apparatus of the character described, a closed treating tank, means for constantly agitating the impregnating material therein, heating means for said tank having an inlet and an outlet, means governed by variations in the temperature of the impregnating material within the treating tank for controlling the inlet of said heating means, and means controlled by va-

- riations in the heating fluid at the outlet side of said heating means for controlling the outlet thereof.
10. In an apparatus of the character described, a treating tank, means for constantly circulating the impregnating material through said tank by taking the impregnating material out of the bottom of the tank and introducing it at the top thereof, heating means for said tank, and means for governing the heat supply to said heating means by variations in the temperature of the impregnating material within the treating tank.
15. 11. In an apparatus of the character described, a closed treating tank, means for constantly agitating the impregnating material therein, means for supplying heat to said tank, and means for maintaining the impregnating material within the tank substantially at a constant pressure.
20. 12. In an apparatus of the character described, a closed treating tank, means for supplying heat to said tank, and means for supplying impregnating material to said tank at substantially a uniform pressure.
25. 13. In an apparatus of the character described, a closed treating tank, means for heating the impregnating material therein, a supply line in communication with said tank, and means for maintaining a constant flow of impregnating material within said supply line at a substantially constant pressure.
30. 14. In an apparatus of the character described, a treating tank, means for constantly circulating the impregnating material through said tank by taking the impregnating material out of the bottom of the tank and introducing it at the top thereof, a storage tank, means for heating said tanks, a supply line leading from and returning to said storage tank and in open communication with said treating tank, means for constantly pumping the impregnating material from the storage tank into the supply line, and means at the discharge end of the supply line for controlling the pressure within said line.
35. 15. In an apparatus of the character described, a treating tank, means for heating the same, automatically operated means for controlling the supply of heat to said heating means, and automatically operated means for maintaining the impregnating material within said tank at a substantially uniform pressure.
40. 16. In an apparatus of the character described, a closed treating tank, means for agitating the impregnating material therein, means for heating said tank, means for governing the heat supply to said heating means by variations in the temperature of the impregnating material within said treating tank, and means for supplying the impregnating material to said tank substantially under constant pressure.
45. 17. In an apparatus of the character described, a closed treating tank, means for constantly agitating the impregnating material therein, means for heating said tank, means for governing the heat supply to said heating means by variations in the temperature of the impregnating material within said treating tank, a supply line in open communication with the tank, and means for maintaining a constant flow of impregnating material under substantially constant pressure within said supply line.
50. 18. In an apparatus of the character described, a closed treating tank, means for heating said treating tank, a charging tank, a storage tank, means in the storage tank for transferring the impregnating material from the bottom of the treating tank to the inlet of said treating tank and for transferring, at will, the impregnating material from the storage tank into the treating and charging tanks and from the treating and charging tanks back into the storage tank, a supply line leading from and discharging into said storage tank and in open communication with said treating tank, and means for maintaining the material in said supply line at a substantially constant pressure.
55. 19. In an apparatus of the character described, a plurality of treating tanks, means for heating each of said tanks, and means common to all of said tanks for maintaining the impregnating material therein substantially at a constant pressure.
60. 20. In an apparatus of the character described, a plurality of treating tanks, means for supplying heat to said tanks, and means common to all of said tanks for supplying impregnating material to said tanks at substantially a uniform pressure.
65. 21. In an apparatus of the character described, a plurality of treating tanks, means for heating each of said tanks, a supply line in open communication with all of said tanks, and means for maintaining a constant flow of impregnating material within said supply line at a substantially constant pressure.
70. 22. In an apparatus of the character described, a plurality of treating tanks, means for heating each tank, means for governing the heat supply to each tank by variations in the temperature of the impregnating material within the respective tanks, a supply line in communication with each tank, and means for maintaining a constant flow of impregnating material within said supply line at a substantially constant pressure.
75. 23. In an apparatus of the character described, a storage tank, a plurality of heating tanks arranged thereabout, means for constantly circulating the impregnating

- material through each tank by taking the impregnating material out of the bottom of the tank and introducing it at the top thereof, means for heating said tanks, a 5 supply line leading from and returning to said storage tank and in communication with all of said treating tanks, means for constantly pumping the impregnating material from the storage tank into the supply 10 line, and automatically controlled means for governing the discharge of impregnating material from the supply line back into the storage tank.
24. In an apparatus of the character described, a storage tank; a plurality of units arranged thereabout, each unit comprising 15
- a treating tank, a charging tank, a pump in the charging tank for continuously circulating the impregnating material in the treating tank and pumping the material 20 from and back into the storage tank, at will; a supply line leading from and returning to said storage tank and in open communication with all of said treating tanks, means for maintaining a constant flow of impregnating material within said supply line at a substantially constant pressure, and means for shutting off, at will, each of the treating tanks from said supply line. 25
